UNITED STATES PATENT OFFICE.

RICCARDO VOLTOLINI, OF WATERBURY, CONNECTICUT.

VENTILATED SHOE.

1,369,590.

Specification of Letters Patent. Patented Feb. 22, 1921.

Application filed June 14, 1920. Serial No. 388,957.

To all whom it may concern:

Be it known that I, RICCARDO VOLTOLINI, a citizen of the Kingdom of Italy, residing at Waterbury, in the county of New Haven 5 and State of Connecticut, have invented new and useful Improvements in Ventilated Shoes, of which the following is a specification.

This invention comprehends the provision 10 of a ventilated shoe, having a narrow pocket at the heel of the shoe, to establish communication between the interior of the shoe and the atmosphere, this cushioning device arranged within the shoe and operating with 15 in the depression and the lift, to provide for the circulation of air within the shoe.

Another object of the invention resides in the provision of an insole for the shoe, which is perforated, and also provided with continuous strips on one side which are spaced defining continuous channels through which the fresh air is forced so as to ventilate the shoe over the entire area of the insole. 20

The nature and advantages of the invention 25 will be better understood when the following detail description is read in connection with the accompanying drawings, the invention residing in the construction, combination and arrangement of parts as 30 claimed.

In the drawings forming part of this application like numerals of reference indicate similar parts in the several views, and wherein:—

35 Figure 1 is a rear elevation of the shoe constructed in accordance with the invention.

Fig. 2 is a transverse sectional view 40 through the shoe looking in the direction of the heel thereof.

Fig. 3 is a sectional view taken at right angles to Fig. 2.

Fig. 4 is a plan view of the heel lift.

Fig. 5 is a plan view of the insole.

45 Fig. 6 is a detail view of the cushioning member.

In accordance with the present invention, I provide the heel portion 10 of the shoe with spaced openings 11 which are covered 50 at one side by a strip of suitable material indicated at 12, and secured to the inside of the heel portion of the shoe to define by the intervening space therebetween air-pockets 13. The strip is cut away at its lower 55 edge at spaced intervals to provide a plurality of openings 14 which together with the

openings 11 establish communication between the interior of the shoe and the atmosphere through the air pocket 13. The heel portion proper including the lift 15 is 60 formed with a depression 16 in which is arranged a cushioning member such as is illustrated in Fig. 6. The cushioning member embodies upper and lower plates 17 and 18 respectively, which are connected together by means of a coiled spring 19. The upper plate is provided with a plurality of spaced openings at 20 to admit the fresh air into the shoe from the pocket 13. 65

Forming a part of the shoe is an insole 21 which is perforated as at 22, one side of the sole being provided with a plurality of spaced inlets 23, which define continuous channels 24 to convey the fresh air to all parts of the shoe over the entire area of the 75 sole. The outermost strip 23 is cut away at spaced points adjacent the heel portion of the sole, to provide passages 26 communicating with the openings 12, so that the air admitted to the shoe from the pocket 13 80 may enter the channels defined by the spaced openings between this outermost strip and the next strip 23. The insole is provided with an opening 27 adjacent the heel which co-incides with one of the openings in the 85 uppermost plate 17 of the cushioning member so as to admit air into the channel defined by the space between the other strips of the sole as shown in Fig. 5. In the practical use of the invention, air is sucked into 90 the shoe through the air pocket, as the heel is lifted, and when the heel is lowered or depressed, this air is forced around the channels of the insole, while the quantity of the foul air is exhausted through the air 95 pockets and the openings 11 of the shoe. It will be noted that the openings 11 are disposed at a reasonably high point in the heel, so as to minimize the possibility of rain water, snow or the like gaining access to the 100 shoe through these openings.

While it is believed that from the foregoing description, the nature and advantages of the invention will be readily apparent, I desire to have it understood that I 105 do not limit myself to what is shown and described, and that such change may be resorted to when desired as fall within the scope of what is claimed.

What I claim is:—

110 A shoe having a pair of spaced openings in the heel portion of the shoe upper, a piece

of material arranged within the shoe and having one end overlying said openings, and its opposite end terminating immediately above the heel lift of the shoe, said lower end of the material having a plurality of openings to establish communication between the pocket defined by the intervening space between the heel portion of the shoe and said piece of material, and the interior 10 of the shoe, a perforated insole, strips extending about the under side of the insole to provide channels, the outermost strip be-

ing cut away at spaced points adjacent the heel portion thereof to provide passages communicating with the openings in said 15 piece of material, a cushioning device embedded in the heel lift beneath the insole and operating to create a circulation of air within the shoe, and said insole having an opening immediately above the cushioning device as described.

In testimony whereof I affix my signature.

RICCARDO VOLTOLINI.
